DESIGN FOR A TAPE OR SIMILAR ARTICLE

James V. Granitto, Milford, Conn., assignor to
The A. J. Donahue Corporation, Milford, Conn., a corporation of Connecticut

Application June 3, 1947, Serial No. 139,423

Term of patent 14 years

(Cl. D3—32)

To all whom it may concern:

Be it known that I, James V. Granitto, a citizen of the United States of America, residing in Milford, in the county of New Haven and State of Connecticut, have invented a new, original, and ornamental Design for a Tape or Similar Article, of which the following is a specification, reference being had to the accompanying drawing, forming part thereof.

In the drawing:

Fig. 1 is a plan view of a tape embodying my new design; and

Fig. 2 is a side elevation thereof.

I claim:

The ornamental design for a tape or similar article, as shown.

JAMES V. GRANITTO.
